US00D740846S

(12) United States Design Patent
Mitchell et al.

(10) Patent No.: US D740,846 S
(45) Date of Patent: * Oct. 13, 2015

(54) COMPUTING DEVICE DISPLAYING GRAPHICAL USER INTERFACE FOR PROVIDING COLLABORATIVE RESOURCES

(71) Applicant: Hewlett-Packard Development Company, L.P., Houston, TX (US)

(72) Inventors: April Slayden Mitchell, San Jose, CA (US); Jay Wilkinson, Salt Lake City, UT (US); Dona Williams, San Francisco, CA (US)

(73) Assignee: Hewlett-Packard Development Company, L.P., Houston, TX (US)

() Term: 14 Years

(21) Appl. No.: 29/509,514

(22) Filed: Nov. 18, 2014

(57) CLAIM

The ornamental design for a computing device displaying graphical user interface for providing collaborative resources, as shown and described.

DESCRIPTION

The sole FIGURE is a front view of a computing device displaying graphical user interface for providing collaborative resources.

The broken lines are for the purpose of illustrating text and environmental structure, and form no part of the claimed design.

1 Claim, 1 Drawing Sheet
